BRAKE HANGER

David M. Light, Chicago, Ill., assignor to American Steel Foundries, Chicago, Ill., a corporation of New Jersey

Application November 1, 1941, Serial No. 417,465

12 Claims. (Cl. 188—209)

My invention relates generally to a brake arrangement for a railway car truck and particularly to a novel form of hanger associated therewith.

The general object of my invention is to devise a novel form of brake hanger which may be resiliently supported from an adjacent brake frame member and conveniently applied or removed as may be desired.

A specific object of my invention is to devise a novel form of brake hanger and support arrangement wherein the truck frame member may be formed with angularly arranged support means on which may be resiliently carried my novel brake hanger wear block and from which may conveniently be supported a brake hanger of usual form.

My invention comprehends an arrangement wherein the brake frame bracket may be so formed as to slidably receive my novel wear block, both said wear block and said bracket being arranged for the interposition therebetween of resilient means, in order that wear between the parts may be reduced.

In my novel arrangement the brake frame bracket may provide support for said wear block at opposite sides thereof and the brake hanger may depend through an opening formed in said wear block in alignment with a slot formed in said bracket.

In the drawings,

Figure 1 is a side elevation of my novel brake hanger arrangement, only a fragmentary portion of the frame member being shown and likewise a fragmentary portion of the brake beam and the adjacent wheel.

Figure 2 is a fragmentary top plan view of the structure shown in Figure 1, and Figure 3 is an end view thereof, taken from the left as seen in Figure 1 approximately in the plane indicated by the line 3—3.

Figure 4 is a view taken from the right as seen in Figure 2 approximately in the plane indicated by the line 4—4 and illustrating the frame bracket only.

Figure 5 is a sectional view through the frame bracket, the section being taken approximately in the longitudinal vertical plane indicated by the line 5—5 of Figure 3.

Figures 6, 7, 8, and 9 show in enlarged size the detail of my novel form of wear block, Figure 6 being a top plan view thereof, Figure 7 a side elevation, Figure 8 a side view thereof taken from the right as seen in Figure 7 approximately in the plane indicated at 8—8, and Figure 9 a sectional

view transversely through the wear block approximately in the plane indicated by the line 9—9 of Figure 7.

Describing the structure in detail, the truck side frame member 2 comprises the inturned end bracket 4 from which may be supported the brake hanger 6. The lower end of said hanger may have pivotal connection as at 8 to the brake head 10, said brake head being secured as at 12, 12 on the end of the beam 14 and supporting in usual manner the brake head 16 for engagement with the periphery of the adjacent wheel 18. Inwardly of the wheel, the brake beam 14 may have secured thereto the fulcrum 20 for connection to operating means in usual manner.

The bracket 4 may be a box-like structure comprising a top wall 22, a rear wall 24, a diagonally arranged bottom wall 26, an end wall 28, and a vertical web 30 parallel with said end wall but spaced therefrom so that the hanger 6 may be supported therebetween. The bottom wall 26 may be slotted as at 31 in alignment with the space between the walls 28 and 30 and the top face thereof may be diagonally arranged so that under normal conditions the hanger 6 will be supported approximately at right angles to said bottom wall or ledge 26, thus avoiding a resultant of forces tending to drag the hanger off the shelf or ledge 26. The end wall 28 and the spaced web 30 may be cored away at their lower edges, the bottom edges thereof being diagonally arranged and parallel with the diagonally arranged bottom wall 26. The bottom edges of the wall 28 and the web 30 may be slotted as at 32, said slots being aligned for accommodation of the brake hanger supporting threaded bolt or pin 34. The upper end of the hanger 6 may have pivotal connection as at 36 with my novel form of wear block generally designated 38, 40 said wear block being slidably received in the end of the bracket 4 and being insertable therein from the inner and open face thereof as viewed at 4—4 (Figure 2). Thus the wear block 38 may seat on the bottom wall 26 at opposite sides of the slot 31, the portions of said bottom wall thus forming a jaw-like structure between which the hanger 6 may depend, while at the same time, the spaced walls 28 and 30 form rigid means together with the adjacent upstanding portions or flanges 42, 42 of said wear block for the hanger securing pin 34.

The said block 38 may be a generally rectangular structure with a bottom wall 40 having the central rectangular brake hanger slot 41 and formed with upstanding lateral flanges 42, 42,

said lateral flanges being formed with aligned perforations and said bottom wall slotted to define the pin opening 44 within which may be received the securing pin 34, already referred to. On the bottom face of the wall 40 and at opposite sides thereof may be secured parallel rubber pads 46, 46, said rubber pads being vulcanized thereto or otherwise secured as may be convenient.

It will be understood that the rubber pads 46, 46 afford bearing for the wear plate or wear block 38 on the bottom wall 26 and after said wear plate has been inserted in normal position, the upper end of the hanger 6 may be elevated into normal relationship therewith, after which the securing pin may be inserted. With the securing pin in place the wear block and the hanger are firmly seated and the hanger is afforded sufficient resilience to reduce noise and greatly lessen wear between the parts.

It is to be understood that I do not wish to be limited by the exact embodiment of the device shown which is merely by way of illustration and not limitation as various and other forms of the device will, of course, be apparent to those skilled in the art without departing from the spirit of the invention or the scope of the claims.

I claim:

1. In a vehicle, a frame member having a bracket, a supporting wheel, said bracket having a bottom wall with a diagonally arranged top surface, a vertical web spaced from said wall, a wear plate seated on said wall with upstanding members having openings aligned with a slot in said web, a securing pin in said openings, a brake hanger hung from said pin and supporting a brake head and brake shoe for engagement with the periphery of said wheel, said hanger normally projecting approximately at right angles to said surface when said shoe is in abutment with said wheel, and spaced resilient means between said plate and said wall.

2. In a brake arrangement, a frame member having a transversely arranged bracket with a bottom wall and spaced vertical means having clearance from said wall, a hanger supporting wear plate inserted between said wall and means with upstanding members adjacent said means, openings in said members aligned with slots in said means, a securing pin in said openings, a brake hanger supported from said pin and extending through said wall, and resilient means under compression between said plate and said wall.

3. In a brake hanger arrangement, a side frame member having an inturned hollow bracket comprising a diagonally arranged bottom wall and spaced vertical walls having clearance from said bottom wall, a wear plate seated on said bottom wall and having upstanding flanges adjacent said vertical walls respectively, a securing pin fixed in said flanges through openings aligned with slots in said vertical walls, and a brake hanger supported from said pin and extending through said bottom wall.

4. In a brake arrangement, a frame member having a bottom wall and spaced vertical webs, said webs being spaced from said wall to define slots therewith, a wear plate positioned in said slots, upstanding means on said plate vertically

overlapping said webs, means securing said upstanding means to said webs, and a brake hanger mounted on said securing means.

5. In a brake hanger bracket, a frame member having a rear web, a bottom wall integral therewith and having a hanger opening, spaced vertical walls at opposite sides of said opening, said vertical walls being spaced throughout their length from said bottom wall to define therewith wear plate slots open at the edges of said walls remote from said rear web, and slots in said vertical walls for the reception of a securing pin.

6. In a brake arrangement, a frame member having a transversely arranged bracket with a bottom wall and spaced vertical webs having clearance from said wall, a hanger supporting wear plate inserted between said wall and webs, with upstanding members adjacent said webs, openings in said members aligned with slots in said webs, a securing pin in said openings, and a brake hanger supported from said pin.

7. In a brake hanger bracket, a frame member having a bottom wall with a hanger opening therethrough, spaced vertical walls at opposite sides of said opening, said vertical walls being spaced from said bottom wall to define therewith wear plate slots opening at the forward edges of said walls, and slots in said vertical walls for the reception of securing means.

8. In a brake arrangement, a longitudinal frame member having a transverse hollow bracket with a bottom wall and vertical means spaced from said bottom wall, a wear plate inserted between said wall and means with upstanding means having aligned pin openings, a securing pin in said openings, a brake hanger hung from said pin, and spaced resilient means between said plate and said wall.

9. A brake hanger wear plate comprising a bottom wall with a hanger slot therethrough, upstanding flanges on the edges of said wall at opposite sides of said slot, and perforations through said flanges aligned with spaced channels in said wall at opposite sides of said hanger slot, said perforations and said channels defining an opening for the reception of a securing member.

10. In a brake arrangement, a longitudinal frame member having a transverse hollow bracket with a diagonally arranged bottom wall and vertical webs spaced from said bottom wall, a wear plate inserted between said wall and webs with upstanding means having aligned pin openings, a securing pin in said openings, and a brake hanger hung from said pin.

11. A brake hanger wear plate of generally rectangular form comprising a bottom wall with a rectangular hanger slot therein, upstanding flanges at opposite edges of said plate, openings in said flanges aligned with a transverse channel in said bottom wall for reception of a securing pin, and resilient means fixed at spaced points on said bottom wall.

12. A brake hanger wear plate comprising a bottom wall with a hanger slot therein, upstanding means at opposite edges of said plate, and openings in said means aligned with a transverse channel in said bottom wall for reception of a securing pin.

DAVID M. LIGHT.
